(57) **CLAIM**

The ornamental design for a hydrogen generator, as shown and described.

DESCRIPTION

FIG. 1 is a perspective view of a hydrogen generator according to the new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof, and,

FIG. 8 is a bottom view thereof; and,

FIG. 9 is a reference perspective view showing a state in which a display panel of the hydrogen generator is opened. The broken lines shown represent the portions of the hydrogen generator that form no part of the claimed design.
